UNITED STATES PATENT OFFICE.

THOMAS R. S. BULLOCK, OF PROVIDENCE, RHODE ISLAND.

CUSHION FOR BILLIARD-TABLES.

SPECIFICATION forming part of Letters Patent No. 613,407, dated November 1, 1898.

Application filed March 18, 1898; Serial No. 674,301. (No model.)

To all whom it may concern:

Be it known that I, THOMAS R. S. BULLOCK, a citizen of the United States, residing at Providence, in the county of Providence and 5 State of Rhode Island, have invented certain new and useful Improvements in Cushions for Billiard-Tables, of which the following is a specification, reference being had therein to the accompanying drawings.

10 The cushions of billiard-tables are composed usually of caoutchouc, or so-called "india-rubber." On account of certain disadvantages which are inherent in this material various attempts have been made to improve 15 upon the construction of the cushions and to provide the necessary elasticity and other characteristics without being dependent altogether upon the elasticity of the rubber itself. The latter has the drawback that after being manufactured and applied it gradually 20 changes and loses its desirable characteristics. It ceases to possess the requisite lively elasticity and becomes more or less stiff and inert, so that after a comparatively short period it becomes necessary to replace cushions 25 composed thereof by new ones. The cost of the material, moreover, is considerable. So far as I am aware none of the endeavors to dispense in whole or in part with the rubber 30 and to attain the same results by other means have been successful, and I am unacquainted with any form of billiard-cushions which has responded satisfactorily to practical requirements and met or withstood the tests or 35 conditions of practical use in which solid-rubber cushions have been replaced by substitutes therefor.

The object of my invention is to provide an improved construction of billiard-cushions 40 which shall be equal in all respects to the best forms of cushions now in use having the bodies thereof composed of india-rubber in which shall be embodied correct and scientific principles of construction and the correct action 45 and which shall not depend wholly upon the employment of india-rubber for the attainment of the desired results.

The invention will be described first with reference to the accompanying drawings, in 50 which I have illustrated the best embodiment of the invention which I have thus far contrived, after which the distinguishing charac-

teristics of the invention will be more particularly pointed out and distinctly defined in the claims at the close of this specification. 55

In the drawings, Figure 1 is an isometric of part of a billiard-table having applied thereto the said embodiment of my invention, with the cloth which covers the cushion removed. Fig. 2 is a view of the same part in 60 cross-section on the same plane of section, substantially as in Fig. 1, with the covering-cloth in place. Fig. 3 is an isometric of one of the springs detached.

1 designates the impact-receiving portion 65 or nose of the cushion.

2, 2, &c., designate a series of springs arranged side by side in the direction of the length of the cushion. The said springs are mounted close together side by side and extend into proximity to the apex or edge of 70 the said impact-receiving portion or nose. The individual springs of the said members are independently movable.

3 designates the cushion-cover, which is composed of cloth, as usual. 75

I form the impact-receiving portion or nose of elastic material, such as rubber, and, as shown, I shape the same and the parts in connection with which it is employed so that the 80 top of the cushion, the edge portion or apex thereof, which cooperates with the balls, and the outwardly and downwardly sloping face thereof all correspond in form and proportions with the cushions of approved manufacture 85 which are now in use. The preferred form of spring which I employ in combination with the impact-receiving portion consists of a blade spring-shaped, substantially as shown. One extremity of the spring is connected with the 90 impact-receiving portion or nose 1, preferably by embedding it in the rubber of which said portion or nose is formed and securing it in place therein by the process of vulcanization. The other extremity of the spring is held securely in a suitable fixture or support. The 95 said fixture or support consists herein of two strips or moldings 4 and 5. What is herein shown as the horizontal portion of the spring is clamped between the two strips or 100 moldings 4 and 5 in the manner which is illustrated in Figs. 1 and 2, the free end of this horizontal portion being bent vertically at right angles to fit against the edge of one

of the strips or moldings, as 4, to prevent the withdrawal of the horizontal portion of the spring from between the two strips or moldings 4 and 5. The strips or moldings 4 and 5 are held together by nails 6, passing between adjacent springs 2 2, and by the aid of glue applied between the strips or moldings. The portion of the spring which has the impact-receiving portion or nose 1 connected therewith extends upwardly substantially parallel with the sloping face of the cushion, as shown clearly in Figs. 1 and 2. I bend the upper end of the spring into hook or recurved form, substantially as shown. This accomplishes a threefold purpose. In the first place it prevents retraction or withdrawal of the spring from the impact-receiving portion or nose. In the second place it prevents the end of the spring from puncturing the said impact-receiving portion or nose or the cover-cloth when a blow is received from a ball or other object. In the third place it causes a greater proportionate part of the rubber to be compressed by a blow from a ball against the edge of the cushion and brings the elasticity of the rubber more fully into play, allowing it to act with greater effect in coöperation with the elasticity of the individual spring or springs which have been flexed by the blow of the ball, thereby giving more speed to the ball. In explanation of this last point it is noted that it will be obvious that when a ball strikes adjacent one of the springs, compressing the impact-receiving portion or nose 1 and bending the spring, the spring itself will have bearing at different points or places within the body of the rubber along the line of force, so that as a result of the bending or flexure of the spring a more uniform compression of the rubber will take place within the body of the impact-receiving portion or nose 1 from the ball outwardly to the fixed abutment, which is constituted by the strip or molding 5. The impact-receiving portion or nose 1 bears along its outer edge against the said strip or molding 5. The support vertically of the said portion 1 might be derived wholly from the springs 2 2. I prefer, however, to rabbet the strip or molding 5 and to rest the outer edge of the impact-receiving portion 1 on the shoulder 7, which is thus produced, this being shown clearly in Figs. 1 and 2.

To secure the portion 1 to the strip or molding 5, I apply glue or cement to the contacting surfaces. I also drive brads 8 downward through the impact-receiving portion or nose 1 into the said strip or molding 5. For the purpose of reinforcing the rubber of the portion 1, so that the brads 8 shall not tear out of the same, I embed and vulcanize in the said rubber one or more plies or layers of cloth or the like, as at 81, at an intermediate place in the thickness thereof, and in driving the brads I cause them to pass through the reinforce 81. The cushion-cover 3 is secured to the upper strip or molding 5 by

means of the cleat or securing-strip 10 and after passing across the top of the said strip or molding 5 and the top of the impact-receiving portion 1 is carried around the edge of the latter down and under the strip or molding 4, to the under side of which it is secured or attached in suitable manner. The edge of the strip or molding 4 adjacent the elbow of the spring 2 is cut away or beveled off, as at 11, in order to prevent contact of the spring therewith in the recoil or vibration of the spring which follows from the blow of a ball.

The force which is transmitted through the impact-receiving portion of the cushion exerts itself in a substantially horizontal direction outwardly to the fixed abutment, which latter in the present case is constituted by the strip or molding 5. Should the blow of the ball against the inner edge of the cushion act to raise such edge above such line and permit the ball to make contact with a more or less extended portion of the face of the cushion, the liveliness of the recoil would be lessened and the quality of the action would be injured. To guard against such raising of the edge of the impact-receiving portion 1, I proportion the upwardly-extending portion of the spring 2 substantially as shown, so that its upper end shall be confined substantially to movement along the line of force—that is to say, its upper end shall not be permitted to rise above the line or lines in which the pressure derived from the ball exerts itself outwardly.

As will be apparent, the elastic material of which the impact-receiving portion or nose of the cushion is formed itself yields or bends at the place of impact to the blow of the ball, and by its reaction or recoil contributes to effecting the return play of the ball. In consequence of the use of a series of independently-movable springs mounted in the cushion close together side by side only those springs which are immediately adjacent to the point at which the ball strikes the cushion are bent or flexed as a result of such blow. The individual springs are proportioned as to their stiffness and resiliency in accordance with the degree of liveliness desired, and they, respectively, are made capable of responding with the desired degree of readiness. It is obvious that were a continuous strip or sheet of steel employed a considerable portion of the length thereof would be affected by the blow of the ball. The greater resistance to bending which is offered by the continuous strip or sheet aforesaid acts with a deadening effect, which destroys or injures the quality and action of the cushion, and if it be sought to avoid this deadening effect by increasing the flexibility of the continuous strip or sheet the cushion is rendered correspondingly inert.

In the illustrated embodiment of the invention the elasticity or resiliency of the rubber of which the impact-receiving portion or

nose 1 is composed is utilized fully—that is to say, the said impact-receiving portion or nose 1 is so combined with the strip or molding 5 that the latter constitutes an abutment therefor, the said strip or molding in turn resting against the top and bottom portions of the side rail 12. Hence when a ball strikes a blow against the edge of the said impact-receiving portion or nose 1 the rubber is compressed between the ball and the backing, thereby enabling the elasticity or resiliency of the rubber to react from the abutment constituted by the said backing. This is an advantage which is incident to the illustrated embodiment of the invention; but I do not confine my invention to constructions in which the rubber rests against a backing. The special aim of the invention is to obviate the disadvantages which are due to the changes which take place in the rubber which is employed usually in the manufacture of cushions for billiard-tables, this change involving the diminution or loss of the elasticity of the rubber, so that in course of time the cushion becomes comparatively dead and lifeless. The springs which are employed in accordance with my invention should be sufficient to give to the cushion the requisite elasticity and liveliness. They should therefore be of such character or quality and should be so proportioned in all respects that when in a construction corresponding with that which is illustrated in the drawings the rubber changes and deadens with age the springs will continue to maintain the requisite elasticity and liveliness.

I claim as my invention—

1. The improved billiard-cushion comprising the impact-receiving portion or nose of elastic material, such as rubber, and the series of independently-movable springs mounted therein close together side by side and extending into proximity to the apex or edge of the cushion, substantially as described. 40

2. The combination with the impact-receiving portion or nose 1 of a billiard-cushion, the same being composed of yielding material, of a series of bent springs as 2, 2, having hooked or recurved upper ends which are embedded in said impact-receiving portion or nose, and a support to which the said impact-receiving portion or nose and the springs are applied, substantially as described. 45 50

3. The combination with the impact-receiving portion or nose 1 of a billiard-cushion, the same being composed of yielding material, of a series of bent springs, as 2, 2, to the ends of which the said impact-receiving portion or nose is applied, and a support to which the said impact-receiving portion or nose and the springs are applied, the said springs being confined from movement above the line or lines of force intermediate the edge of said yielding portion 1 and the backing or abutment for the said portion, substantially as 55 60 65 described.

In testimony whereof I affix my signature in presence of two witnesses.

THOMAS R. S. BULLOCK.
